UNITED STATES PATENT OFFICE

153,766

DESIGN FOR A COMBINED SIGNAL LIGHT AND ASH RECEIVER

Arthur C. Conner, Salt Lake City, Utah

Application October 13, 1947, Serial No. 141,882

Term of patent 3½ years

(Cl. D72—1)

To all whom it may concern:

Be it known that I, Arthur C. Conner, a citizen of the United States, residing at Salt Lake City, county of Salt Lake, and State of Utah, have invented a new, original, and ornamental Design for Combined Signal Light and Ash Receiver, of which the following is a specification, reference being had to the accompanying drawing, forming part thereof.

In the drawing:

Fig. 1 is a perspective view of a combined signal light and ash receiver showing my new design; and

Fig. 2 is a top plan view of the combined signal light and ash receiver shown in Fig. 1.

I claim:

The ornamental design for a combined signal light and ash receiver, as shown.

ARTHUR C. CONNER.
